UNITED STATES PATENT OFFICE

CLIFFORD J. MCLEOD, OF QUINCY, MASSACHUSETTS

VALVE-SILENCING MECHANISM

Application filed September 26, 1928. Serial No. 308,415.

This invention relates to mechanism for reducing noise and wear incident to the operation of poppet valves such, for example, as are in use on many makes of internal combustion motors. Valves of this type are customarily closed by springs and are opened against the force of the springs by the pressure of some member such as the end of a rocker arm against the end of the valve stem. 10 When the rocker arm or other valve-opening member moves to permit the valve to close under the action of its spring, the arm must ordinarily be adjusted to move clear of the valve stem when the valve closes, in order to allow the valve to seat tightly. Thus the valve in closing hits its seat with the full pressure of the valve spring on it. This causes considerable noise and wear. When the rocker arm starts its valve-opening motion, it must first take up the clearance space between it and the end of the valve stem before engaging the stem to open the valve. This causes a click between the arm and stem which adds to the noise and wear. According to the present invention I greatly reduce the noise and wear on the valve and its associated parts by means of a simple and effective device for resiliently opposing the action of the valve spring until the valve is seated, and for maintaining the valve stem and rocker-arm in mutual contact at all times. Various advantageous features of construction will be apparent to one skilled in the art from the description of the invention which follows, and from the drawing, of which:

Figure 1 is a perspective view of an element employed in the mechanism.

Figure 2 is a side elevation of the same.

Figure 3 is a side elevation of a rocker bar formed for use with the element shown in Figure 1.

Figure 4 is a side elevation, partly broken away and in section of a poppet valve with valve opening mechanism and valve silencing mechanism.

Figure 5 is a similar view showing the parts in a different position of operation.

Figure 6 is a perspective view of a modified form of element for valve silencing mechanism.

Figure 7 is a flanged pin for use with the element shown in Figure 6.

Figure 8 is a section of a rocker arm adapted to cooperate with the elements shown in Figures 6 and 7.

Referring to the drawing in detail, 10 represents a rocker bar which is adapted to rock on a shaft 11 in order to open a poppet valve 12 which is constantly pressed toward its closed position by a valve spring 13. The spring may be as usual a helical coil under compression between the motor casing 14 and a washer 15 which is secured adjacent to the end of the valve stem 16. The rocker bar 10 is provided with an arm 17, motion of which serves to open the valve 12 or to permit it to close under the action of the spring 13. The valve-opening motion of the arm 17 may be produced as by a push-rod 18 which engages the opposite end of the rocker bar 10. In ordinary valve construction, the outer end of the rocker arm 17 directly engages the end of the valve stem 16. In order to permit the valve to seat tightly, a small clearance between the end of the arm 17 and the end of the valve stem must be allowed as otherwise any wear on the valve seat or the contacting face of the valve would result in a failure of the valve to close tightly. According to this invention a resilient contact is established between the end of the arm 17 and the end of the valve stem so that the click usually incident to the meeting of the rocker arm and the valve stem is thus avoided. To this end a rockable element or shoe 19 may be provided, this shoe being carried by the rocker arm 17 and held thereon against longitudinal or lateral sliding motion, the shoe being free, however, to rock on the arm.

In order to prevent relative longitudinal motion I may provide an interfitting tongue 20 and groove 21. As shown on the drawing, the tongue is formed transversely on the rocker arm 17, the groove 21 being formed in the shoe 19. If desired, however, the tongue may be formed on the shoe, and the groove in the arm. The shoe may be provided with a curved elongated portion 22, this portion serving as a lever arm which may be engaged by a suit-

able leaf spring 23 which is mounted on the rocker bar. The elongated portion 22 may be provided with a pair of flanges or fins 24 which are arranged to engage the side faces 5 of the rocker arm 17 so as to prevent relative lateral or transverse motion between the shoe 19 and the arm 17. The face of the arm which is opposed to the shoe may be recessed as at 25 so that the shoe will normally pivot 10 on a small portion of the face of the arm 17 which is adjacent to an edge 26. The spring 23 may be secured to the rocker bar as by a suitable screw 27 or by any other means. This spring, as shown in Figures 4 and 5, is 15 preferably curved so as to cooperate with the curvature of the extension 22 of the shoe 19 in such a way as to engage the face of the shoe selectively at different points along the length of the extension 22 according to the position 20 of operation of the valve opening and silencing mechanism. When the valve is closed as shown in Figure 4, the end of the spring 23 which is remote from its point of support engages the shoe 19 at a point well spaced 25 from both ends thereof. When the valve is open the parts are as shown in Figure 5 wherein the spring 23 is represented as engaging the shoe 19 at a point near the end of the shoe which is remote from the point of 30 its contact with the valve stem 16. In this position the intermediate portion of the spring rather than its free end engages the shoe 19. As this intermediate portion is nearer to the point of support of the spring 35 than is the free end, the spring thus offers a stiffer resistance, the effect of this resistance on the shoe being magnified by the fact that the lever arm 22 which fulcrums on the surface adjacent to the edge 26 is effectively 40 longer when the valve 12 is open, since the spring 23 in this case engages the extension 22 near the end remote from the fulcrum rather than at a point nearer the fulcrum as in Figure 4. The result of this construction 45 is to oppose an increasing resistance to the rocking motion of the shoe as the valve 12 opens. Thus when the rocker bar 10 is rocked from its position, as shown in Figure 4, in order to open the valve 12, the shoe 19 is 50 pressed against the end of the valve stem 16 and tends to rock on its fulcrum in opposition to the pressure of the spring 23 on its extension 22. As the rocker bar 10 rocks further, an increasing pressure is thus caused 55 between the shoe 19 and the stem 16 by the virtual increase of the lever arm 22 from the fulcrum 20 to the point of contact of the arm 22 with the spring 23, until the tendency of the spring to rock the shoe in one direction 60 is balanced by the pressure against the valve stem 16 which tends to rock the shoe in the opposite direction. Thereupon, further rocking motion of the rocker bar 10 serves to move the valve to its open position. When the 65 valve returns to its closed position, the bal-

ance between the opposing moments on the shoe 19 caused by the pressure of the valve stem 16 at one end of the shoe and the pressure of the spring 23 near the other end of the shoe is maintained until the valve reaches 70 its seat, whereupon the shoe 19 rocks to reduce its pressure against the end of the valve stem when the arm is further withdrawn and thus increasingly to permit the valve spring 15 to press the valve 12 firmly against its seat. In this way the blow of the valve 12 against its seat is minimized since at the instant when the valve reaches its seat, the valve closing pressure of the spring 13 is balanced 75 by the opposing pressure of the shoe 19 against the end of the stem. When the valve reaches its seat, the opposing pressure of the shoe is thereupon reduced as the shoe rocks so as to cause the spring 23 to engage it at a point nearer to its central portion. In 80 order to prevent side slipping of the spring with reference to the extension 22, I may mount in the latter a pin 28 which may extend to a suitable perforation 29 in the spring 23.

Figures 6 and 8 illustrate a modified embodiment of the invention, different means being employed in this embodiment for preventing relative longitudinal and lateral motion between the shoe and the rocker arm. 95 According to this embodiment the rocker arm 30 is provided with a transverse recess 31 near its end. The shoe 32 is likewise recessed as at 33, the recesses 31, 33 being opposite each other so as to form a nearly cylindrical perforation in which may be mounted a pin 34 having flanged ends 35. The body of the pin 34, as shown, forms a pivot on which the shoe may rock and prevents relative longitudinal movement between the shoe and the 100 rocker arm, the flanged ends 35 serving to prevent lateral movement. The recesses 31, 33 may be shaped somewhat as shown in Figure 8 to allow the body of the pin 34 a slight rolling motion as the shoe 32 rocks on the arm 30. This reduces wear on the pin 34 and the contacting faces. The action of the shoe 32 is identical with the action of the shoe 19 which has been hereinbefore described in detail.

Having thus described an embodiment of this invention, it should be evident to those skilled in the art that various changes and modifications might be made therein without departing from its spirit or scope as defined by the appended claims.

I claim:

1. The combination with a valve, a stem thereon, and a valve-closing spring, of a member movable to open the valve against the pressure of the spring, a stem-contacting element rockably carried by said member and arranged to engage said stem adjacent to one end of said element, and a spring secured to said member and engaging said element selec- 130

tively at various points extending from the central portion of the element to the end remote from said stem-engaging end, the point of contact between the element and the element-engaging spring depending on the position of operation of said member and stem.

5. Valve-silencing mechanism comprising a rocker bar having an arm, a valve stem movable by the rocking motion of said arm, and yielding means carried by said arm and engaging said stem, said yielding means including a member having direct rocking contact with said arm, said stem being arranged to bear on one end portion of said member, and 10 a spring bearing on the opposite end portion of said member selectively at various points according to the position of operation of said member.

6. Valve silencing mechanism comprising a rocker bar having an arm, a valve stem movable by the rocking motion of said arm, and yielding means carried by said arm and engaging said stem, said yielding means including a member having direct rocking contact 20 with said arm, said stem being arranged to bear on one end portion of said member, and a spring bearing on the opposite end portion of said member at a point about half-way between the ends of the member when the valve 25 is closed, and at a point near the end of the member when the valve is open.

7. The combination with a valve having a stem and a valve-actuating member, of valve silencing mechanism comprising a cooperating member rockably carried by said valve-actuating member and engaging said stem, said members having a transverse tongue and groove engagement whereby relative longitudinal motion between said members is prevented, one of said members having lateral flanges engaging the other said member to prevent relative transverse motion between said members, and a spring carried by said valve-actuating member and engaging said 40 cooperating member on its end portion remote from the point of engagement with said stem.

8. The combination with a valve, a stem thereon, and a valve-closing spring, of a member movable to open the valve against the pressure of said spring, a stem-contacting element rockably carried by said member and arranged to engage said stem adjacent to one end of said element, and a spring secured to said member and engaging said element selectively at various points extending from the central portion of the element to the end remote from said stem-engaging end, said member and element having opposed faces thereon mutually engageable to prevent longitudinal slip between said element and member.

9. Valve-silencing mechanism comprising a rocker-bar having an arm, a valve stem movable by the rocking motion of said arm,

a member having direct rocking contact with said arm and having an end portion bearing directly on said stem and a spring bearing on the opposite end portion of said member selectively at various points according to the position of operation of said member, said arm and member having opposed faces adjacent to the stem-engaging end of said member and mutually engageable to prevent longitudinal slip of said member on 70 said arm.

10. Valve-silencing mechanism comprising a rocker bar having an arm, a valve stem movable by rocking motion of said arm, a member having direct rocking contact with said arm and having an end portion bearing directly on said stem, and a spring bearing on the opposite end portion of said member, said arm and member having opposed faces adjacent to the stem-engaging end of 80 said member and mutually engageable to prevent longitudinal slip of said member on said arm.

11. Valve silencing mechanism comprising a rocker bar having an arm, a valve stem movable by rocking motion of said arm, a member having direct rocking contact with said arm and having an end portion bearing directly on said stem whereby pressure between said stem and member tends to rock 90 the member on the arm, and a spring bearing on said member and tending to rock said member in opposition to said stem, said arm and member having opposed faces thereon mutually engageable to prevent longitudinal 95 slip of said member on said arm.

12. In testimony whereof I have affixed my signature.

CLIFFORD J. McLEOD.
